United States Patent Office.

ASAHEL C. BOYD, OF WORCESTER, MASSACHUSETTS, ASSIGNOR TO E. W. VAILL, OF SAME PLACE.

Letters Patent No. 105,898, dated August 2, 1870.

IMPROVEMENT IN FOLDING-CHAIR.

The Schedule referred to in these Letters Patent and making part of the same.

To all whom it may concern:

Be it known that I, ASAHEL C. BOYD, of Worcester, in the county of Worcester and State of Massachusetts, have invented a new and improved Folding-Chair; and I do hereby declare the following to be a full, clear, and exact description of the same, reference being had to the accompanying drawing making a part of this specification, in which—

Figure 1 is a side elevation of the chair, open;

Figure 2 is a side elevation of the chair, folded together; and

Figure 3 is a front elevation of fig. 1.

This invention relates to certain improvements in folding-chairs whose front legs extend upward and are jointed at their upper ends to the chair-back.

The invention consists in the combination of the seat and longitudinally-slotted back legs with the side posts of the chair-back, when the same are provided, near their lower extremities, with pins which enter the slots in the back legs; also, in the combination of the above with the jointed arms which connect the side posts with the rear part of the chair-bottom, all in such a manner that, when the chair is folded together, the back may slide upward in the slots of the legs, and, by means of the connecting-bars, raise the chair-bottom until it becomes parallel with and stands in close proximity to the back, and, when the chair is

opened, the back may slide downward in the slots in the legs, and, by means of the connecting-bars, draw the chair-bottom downward into a horizontal position.

In the drawing—

a is the chair-bottom or seat;

b, the front legs;

c, the back legs;

d, slots in the inner sides of the back legs;

f, the side posts of the chair-back;

e, the pins which project from the posts *f* into the slots *d*; and

h, the jointed bars which connect the posts *f* with the rear part of the seat *a*.

Having thus described my invention,

What I claim as new, and desire to secure by Letters Patent, is—

1. The combination of the legs *c*, provided with the slots *d*, side posts *f* of the chair-back, provided with the pins *e*, legs *b*, and seat *a*, substantially as described.

2. In combination with the above, the jointed arms *h*, for the purpose specified.

ASAHEL C. BOYD.
